CUTTER CHAIN

Charles F. Osgood, Claremont, N. H., assignor to
 Sullivan Machinery Company, a corporation of
 Massachusetts

Application February 23, 1935, Serial No. 7,673

2 Claims. (Cl. 262—33)

This invention relates to cutter chains and more particularly to improvements in cutter chains especially designed for use with the cutter bars of coal-cutting machines.

5 An object of this invention is to provide an improved cutter chain having improved means for supporting and holding a cutter bit in cutting position thereon. Another object is to provide an improved bit block and holder for the cutter 10 bit of a cutter chain. Yet another object is to provide an improved cutter block and holder for a cutter bit of the double-ended, reversible type, having embodied therein improved means for securing the cutter bit in cutting position. A still 15 further object is to provide a cutter bit of an improved shape. Yet another object is to provide a cutter bit of the double-ended, reversible type of an improved shape whereby the bit may be supported in an improved manner within its 20 holder. These and other advantages of the invention will, however, hereinafter more fully appear.

In the accompanying drawing there is shown for purposes of illustration one form which the 5 invention may assume in practice.

In this drawing,—

Fig. 1 is a side elevational view of the illustrative form of the improved cutter chain,

Fig. 2 is a cross sectional view taken substantially on line 2—2 of Fig. 1,

Fig. 3 is a view in longitudinal section taken substantially on line 3—3 of Fig. 2,

Fig. 4 is a plan view of the improved cutter bit,

Fig. 5 is an end view of the bit shown in Fig. 4,

Fig. 6 is a cross sectional view taken on line 6—6 of Fig. 4,

Fig. 7 is a perspective view of the improved cutter bit.

In this illustrative embodiment of the invention there is shown a cutter chain especially designed to use with the cutter bar of a coal-cutting machine, comprising a series of bit blocks 1 and side straps 2 pivotally connected together at 3. The bit block 1 has formed in its forward face a bit-receiving socket 4 for receiving a cutter bit 5 of an improved design. Formed in the bit block and communicating with the socket 4 is a longitudinal bore 6 receiving a bolt 7 having threaded thereon at 8 a tightening nut 9, and this bolt has formed on its forward end a clamping portion 10 for engaging the cutter bit 5 for firmly clamping the latter in the socket 4. The cutter bit 5 is of the double-ended, reversible type known as a detachable bit, of triangular form in side elevation and having a plane cutting face 11, herein of

elongated, substantially diamond-shape in contour, having its side edges terminating at the opposite extremities of the bit in cutting points 12 and 13. The bit body is substantially triangular in shape in cross section, as shown in Fig. 6, 5 and is formed with relatively inclined side surfaces 14 intersecting at 15 along a line lying in a transverse plane midway between the ends of the bit, and these plane sides 14 of the bit body incline outwardly toward the bit points and at their 10 outer extremities terminate at the bit points. It is therefore evident that the bit body supporting the plane face 11 of the bit is substantially of pyramidal form, the sides converging to the point 16, remote from the base of the triangle, at the 15 apex of the pyramid. The clamping portion 10 of the clamping bolt 7 fits within the socket in the forward face of the bit block and is formed with a plane surface 17 engageable with the plane 20 face 11 of the bit, and the bit-receiving socket 4 is of wedge shape, formed with inclined side walls conforming with the sides 14 of the bit body and converging to a straight line forming the rear wall 18 of the socket and extending at right angles to the longitudinal axis of the bit block. Extending forwardly and outwardly from the rear wall 18 of the socket is a wall 19 engaging the bit body in advance of the widest portion of the bit body and forming a stop for preventing the endwise 25 release of the bit from the socket 4 when the clamp portion 10 is in its clamping position, this projection preventing bit release even when the clamp portion 10 is slightly loosened. When the cutter bit is placed in its cutting position within the bit-receiving socket 4 and the bolt 7 tightened 30 to move the clamp portion 10 into clamping engagement with the bit face 11, the cutter bit is clamped with a wedging action in position within the socket, with the rear and outwardly inclined edges of the bit body engaging the walls 18 and 19 of the socket and the inclined sides 35 engaging the inclined socket walls, thereby firmly holding the cutter bit in cutting position on the block. When the active cutting point 12 of the bit becomes dull, the clamp 10 may be loosened 40 and the bit turned end for end within its socket, the cutting point 13 at that time being active.

As a result of this invention it will be noted that an improved cutter bit of an improved shape is provided, whereby a more effective cutting operation is attained, while at the same time simplifying the bit supporting and holding means. It will further be noted that an improved cutter chain is provided having an improved bit block and holder, together with improved means for 45 50 55

positively holding the cutter bit in cutting position on the chain. These and other uses and advantages of the invention will be clearly apparent to those skilled in the art.

5 While I have in this application specifically described one form which my invention may assume in practice, it will be understood that this form of the same is shown for purposes of illustration, and that the invention may be modified 10 and embodied in various other forms without departing from its spirit or the scope of the appended claims.

What I claim as new and desire to secure by Letters Patent is:

15 1. In a cutter chain, a bit block having a bit-receiving socket, a double-ended reversible cutter bit of substantially pyramidal form having an elongated, substantially diamond-shaped, plane cutting face at the base of the pyramid terminating in alined cutting points at the bit ends, 20 said socket receiving the sides of the pyramid opposite from its base and having walls disposed to cooperate with at least a portion of each of the bounding surfaces of said bit other than the

cutting face of the latter, and securing means on the bit block and engaging the cutting face of the bit for clamping the bit in said socket.

2. In a cutter chain, a bit block having a recess in its forward face for receiving a cutter bit, 5 a cutter bit of substantially pyramidal form having alined cutting points at the opposite ends of a plane, elongated base which is symmetrical with respect both to a major axis and to a rectangularly-related minor axis, the apex of 10 the pyramid seated in said recess, the latter being shaped to conform to the shape of the bit, and a clamping member engaging the plane surface at the base of the pyramid for clamping the bit in cutting position on the block, the distance between the outermost point of clamping engagement of said clamping member with the bit and the outermost point of the recess on the block being less than the distance between the first mentioned point and the point at the pyramid 15 apex, whereby escape of the bit from its recess even when said clamping member is slightly loosened is precluded.

CHARLES F. OSGOOD.
